DESIGN FOR A COMBINED WASHER AND WRINGER

Zareh George Jigamian, Venice, Calif., assignor
to Donald P. Smith, Balboa, Calif.

Application August 19, 1940, Serial No. 94,495

Term of patent 14 years

To all whom it may concern:

Be it known that I, Zareh George Jigamian, a citizen of the United States, residing at Venice, in the county of Los Angeles, State of California, have invented a new, original, and ornamental Design for a Combined Washer and Wringer, of which the following is a specification, reference being had to the accompanying drawing, forming part thereof.

In the drawing—

Fig. 1 is a perspective view of the front of a

combined washer and wringer embodying the design of my invention;

Fig. 2 is a top plan view of the wringer supporting head and washer of Fig. 1.

The essential features of my design are shown in full lines.

I claim:

The ornamental design for a combined washer and wringer, as shown and described.

ZAREH GEORGE JIGAMIAN.
